CLAIM

The ornamental design for a padel racket as shown and described.

DESCRIPTION

FIG. 1 is a front perspective view of an embodiment of a padel racket.

FIG. 2 is a front view of the padel racket shown in FIG. 1 including a cross-section line.

FIG. 3 is a side view of the padel racket shown in FIG. 1.

FIG. 4 is a top view of the padel racket shown in FIG. 1.

FIG. 5 is a bottom view of the padel racket shown in FIG. 1.

FIG. 6 is a cross-sectional view along the cross-section line of the padel racket shown in FIG. 2.

FIG. 7 is a front perspective view of a second embodiment of the padel racket.

FIG. 8 is a front view of the padel racket shown in FIG. 7 including a cross-section line.

FIG. 9 is a side view of the padel racket shown in FIG. 7.

FIG. 10 is a top view of the padel racket shown in FIG. 7.

FIG. 11 is a bottom view of the padel racket shown in FIG. 7; and,

FIG. 12 is a cross-sectional view along the cross-section line of the padel racket shown in FIG. 8.

The broken lines in the figures illustrate the portions of the padel racket that form no part of the claimed design.
